Patented Dec. 20, 1960

189,470

PORTABLE DISPENSER FOR LIQUID SOAP OR THE LIKE

Hans Joachim Haering, Terminusstrasse, Goldach,
St. Gall, Switzerland

Filed Jan. 11, 1960, Ser. No. 58,989

Term of patent 7 years

(Cl. D86—10)

Fig. 1

Fig. 2

Fig. 4

Figure 1 is a front elevation of a portable dispenser for liquid soap or the like embodying my new design; the rear of the container is substantially the same in appearance except for the omission of the indicia bearing area;

Fig. 2 is a side elevation thereof taken from the right of Fig. 1;

Fig. 3 is a bottom plan view; and

Fig. 4 is a top plan view of the portable dispenser for liquid soap or the like.

I claim:

The ornamental design for a portable dispenser for liquid soap or the like, as shown and described.
